UNITED STATES PATENT OFFICE

EMIL F. SCHONBERGER, OF CLEVELAND, OHIO, ASSIGNOR TO THE SMOKELESS FURNACE
& BOILER CO. INC., A CORPORATION OF OHIO

FURNACE

Application filed October 7, 1929. Serial No. 397,883.

This invention relates to improvements in furnaces, and relates more particularly to furnaces of the so-called "smoke consuming" type.

5 One very difficult problem presented in the operation of furnaces using carbonaceous fuel is the elimination of the smoke and noxious gases. Furnaces incorporating principles that sought to eliminate smoke and the like, 10 have been constructed prior to my invention, but many of such furnaces have involved a complicated structure and still more complicated method of operation and consequently were not of practical utility for the smaller installations.

It is therefore an object of this invention to provide a furnace in which the by-products therefrom are reduced to a minimum.

Another object of this invention is to provide 20 a furnace of the class described which is simple to operate.

Another object of this invention is to provide a furnace in which the various parts most subject to wear may be readily replaced 25 without dis-assembling the entire furnace.

Still another object is to provide for an improved fire box in which the differential expansions of various parts is not as liable to cause breakage thereof.

30 Still other objects of the invention and the invention itself will become more apparent from the following description of an embodiment thereof, and in which description, reference may be had to the accompanying drawings, forming a part of this specification.

In the drawings:

Fig. 1 represents a front elevational view 40 of a furnace embodying the features of my invention; the hot air jacket therefor not being shown;

Fig. 2 is a sectional view taken on the line 2-2 of Fig. 1, looking in the direction of the arrows;

45 Fig. 3 is a side elevational view of the furnace of Fig. 1;

Fig. 4 is a plan view of the furnace with the hot air jacket therefor shown in section;

50 Fig. 5 is a rear elevational view of the furnace of Fig. 1;

Fig. 6 is a fragmentary sectional view, with certain parts being shown in elevation and others illustrated by dotted lines, of a valvular mechanism used to control the operation of the furnace;

Fig. 7 is a fragmentary sectional view taken on the line 7-7 of Fig. 2, the grate bar therefor being shown in elevation;

Fig. 8 is a sectional view taken on line 8-8 of Fig. 2;

Figs. 9 and 10 are enlarged fragmentary sectional views of fragments of the fire box showing details of construction.

Referring now to the figures of the drawings throughout which like parts are designated by like reference characters, the furnace structure comprises generally, a pair of individual fire boxes and combustion chambers interconnected by conduits in such a manner that the products of combustion from one fire may be conducted underneath the adjacent fire and directed upward therethrough.

More specifically the structure includes a substantially cylindrical body 2. A pair of spaced parallel walls 3 divide the cylinder, extending from the bottom of the cylinder to the top thereof, providing an air space through the central portion of the structure, and a pair of semi-cylindrical chambers 4 and 5 on either side thereof. The cylindrical body of the furnace and the dividing wall may be constructed of boiler plate with the edges butt or lap welded. The parallel walls may be braced by a member 91 which bridges the space between the walls. The top and bottom end walls of each of the semi-cylindrical chambers are sealed with semi-circular plates.

The space 6 intermediate the two chambers is open at the top and is bridged at 7 spaced from the bottom by a piece of sheet metal. A pair of oppositely disposed rectangular openings, of which one is shown at 8, are provided through the outer wall adjacent to the bridging member 7, opening into the space 6 to provide an air inlet to allow the air currents to circulate through the passage.

The ash pits are disposed in the lowermost portion of each chamber 4 and 5 and are each provided with an ash door frame 10 and 11,

which may be of cast iron construction, and are secured to the furnace structure by bolts, rivets or the like 9, about apertures in the sheet metal structure. A suitable iron cement 5 may be used to seal the joints. Each frame is provided with an outwardly extending flange 12, to which a hot air jacket may be secured by bolts, or the like. Each ash door frame hingedly supports ash doors 14 through 10 which access may be had to the interior bottom portions of the chambers.

A pair of recesses 15 and 16 are provided in the upper walls of the frames 10 and 11 adjacent to the cylindrical body to provide suitable 15 housings for the grate bar gears 17 and 18.

Each furnace section is provided with a fire box that is spaced from the surrounding walls and which comprises an upper fire pot 20 of 20 semi-cylindrical form, and a lower fire pot 21 upon which the upper portion is adapted to rest the joints between the two being rabbeted to provide a close fit therebetween. The walls of the lower pot 21 incline inwardly, as is 25 well illustrated in Figs. 7 and 10.

A pair of downwardly depending bored bosses 22 are provided at the rear of each fire pot 21 to form rear bearing journals for the grate bars 23. The front ends of the grate 30 bars are supported by the ash door frame as is best shown in Fig. 8, the bars being spaced by a separator 30 and supported by bearings 31. Both the separator and the bearings are provided with squared lugs 32 and 33 which 35 extend through apertures in the door frame casing, the bearings and separator being secured to the casing by bolts 34.

Each fire box 21 is supported within the 40 chamber by retainer cleats 36, which are secured to the furnace wall 2 by bolts or rivets 37. As previously described the walls of the lower pot extend inwardly toward the bottom and the lowermost portion is provided with an 45 outwardly extending flange 35 which is adapted to rest upon the cleats 36 disposed at intervals about the periphery of the furnace structure. The grates, which are supported by the fire pot and by the door frame, are provided with meshed gears 17 and 18 which extend upward into the recesses 15 and 16.

The innermost grate or the one next to the 50 wall 3, is relatively long, and the outer grate is relatively short. The bearing bosses supporting the rear ends thereof are placed in 55 stepped relation to each other about the fire pot. The longer grate bar is provided with a forwardly extending portion which has a squared end to receive a shaker handle by which the grate bars may be rotated. The 60 ash door has small apertures which are covered by wickets such as 40 through which the shaker handle may be inserted.

The ash doors are also provided with large 65 draft doors 41 the purpose of which is commonly known.

Each chamber is provided with an inwardly extending flange 42, which may be of L shaped cross section, and is secured to the furnace wall contiguous to the upper edge of the fire pots 20 and against which the upper 70 edge of the fire pot may be pressed. It may be readily seen, that with a fire pot of sectional construction such as has been described, that the parts may be readily placed within the furnace structure without dismantling the furnace, as the ash pit door is sufficiently large to allow the fire pot sections to be removed or inserted there-through.

In removing the old fire pots the grate bars are first removed and then the bolts are removed from the lugs 36 and the old fire pots dropped and removed through the ash pit doors. In replacing the new fire pots the operation is reversed, the new fire pots being raised into position and the cleats bolted in 85 place. This construction allows the fire pots to expand and contract freely and prevents the same from coming into direct contact with the furnace wall and closes the space between the fire pots and the furnace wall at 90 the upper edge of the fire pot preventing escape of gases from below the fire pot around the periphery thereof.

A pair of inlet flues 43 and 44 are provided including apertures opening into the rear of 95 the ash pit at the lowermost portion of each side of the cylindrical structure and a pair of flues 45 and 46 are provided at the uppermost side of the structure. Flue casings are secured to the furnace structure circumambient the flue apertures. They may be constructed of cast iron and are best shown in Fig. 3.

A pair of fire door casings 47 and 48 are secured to the forward side of the furnace 105 structure spaced from the top slightly above the fire pot 20. The casings may be constructed of cast iron or the like and are secured to the furnace structure in a manner such as has been described for the ash door 110 casing, each casing supporting a fire door 49 which may be provided with a draft inlet 50.

The upper flues 45 and 46 are exhaust flues and are each connected to cast iron conduits 51 and 52 which are of substantially 115 square cross-section. The conduits connect with a stack casing 53 as better illustrated in Figure 4, the stack casing having branched openings to furnish connection to the stack for each of the conduits 51 and 52.

A pair of tortuous conduits 54 and 55, also of rectangular cross-section are provided, and are adapted to connect at their upper ends to the conduits 51 and 52 and at their lower ends to the flues leading into the opposite ash pits, in such a manner that each furnace section has its upper end in communication with the lower end of the adjacent section. This is accomplished by placing the openings in the conduit 51 and 52 in such a 120

manner that one of them is adjacent to the flue casing and the other is adjacent to the stack casing.

Dampers or valves 60 and 61 are provided in the conduits 51 and 52 in such a manner that one conduit may be closed to the stack casing and open to the fire box of the adjacent section while the other conduit is closed to the fire box of the adjacent section and open to the stack casing or vice versa. As best shown in Fig. 6, the dampers are adapted to seat against annular flange 62 in the casing. Each damper is secured to a rod 63 journaled in bearings 64, formed in bosses upon the conduits. The ends of the rod adjacent to the adjoining conduit project beyond the bosses and a pair of segmental gears 66 and 67 are secured thereon. The gears mesh with each other in such a manner that when one damper is rotated by its shaft in a clock-wise direction, the adjacent damper is rotated in a counter-clockwise direction. The rod upon which the damper 61 is secured projects beyond the side of the pipe through the casing 70 and has an operating lever 71 on its end.

A flue hole may be provided in the stack conduit closed by a damper 68.

When the furnace is started in operation, a fire is built in either one of the fire boxes. The first fire will cause a certain amount of smoke. If we consider that the fire is being built in the section 5, to the left as viewed in Fig. 1, the valves or dampers will be so positioned that the conduit leading from the upper part 25 of the chamber 5 through the conduit 51 is open to the stack conduit 53. In this position the tortuous conduit 54 which leads to the lower portion of the fire box of the chamber 4 on the right is closed.

When the fire has become sufficiently incandescent and is burning at that state of combustion wherein little or no smoke is given off, another fire is built in the chamber 4 to the right. The products of imperfect combustion from the green fire are conducted from the upper flue 52 which is closed to the stack flue but opened to the tortuous conduit 55, downwardly through the tortuous passage 55 into the ash pit below the incandescent fire in the chamber 5. The partially burned products of combustion of the second fire caused by the coking of the second fire then ascend through the fully coked fire, through the incandescent coals therein, and are consumed in such a manner that products are burned and when passed through to the stack have now removed therefrom, the majority of combustible products, the gases which escape to the air through the stack, being substantially free from the heavy smudge common to coal fires.

The furnace may now be said to be in full operation and when the fire in the chamber 5, which was first started, becomes sufficiently low to require coaling the damper handle is

revolved in a counter-clockwise direction as viewed in Figs. 4 and 6 which closes the direct communication with the left hand fire to the stack and causes the products therefrom to be sent through the tortuous channel to the ash pit underneath the fire at the right. Simultaneously, the right hand fire has been put into direct communication with the stack with its upper flue. The left hand fire is now 70 coaled and the operation continued in a manner to that previously described.

I find that with this system of alternately fired sections of the furnace, or what is substantially two separate furnaces, that the products of imperfect combustion from the green fire are all substantially consumed in the fire that is in a highly incandescent state.

The construction of the fire box which allows an air space between the fire box proper and the steel structure forming the walls is such that there is very little tendency for the walls of the furnace to warp out of shape, and the angular member 42 prevents the unburned gases from escaping to the stack without passing through the incandescent fire. The grates and fire boxes may be readily replaced if they should burn out, without dismantling the entire furnace structure as is now the general practice.

The drawings illustrate more particularly a furnace structure adapted for hot air heating systems wherein the air circulates through an intake not shown, in the bottom of the housing 70, as is common with hot air furnaces; the air is further assisted in its circulation by entering the inlet aperture 8 at the front and rear, and passing upwardly through the passage 6 out the top of the structure. This same structure may be used for hot water or steam systems, the only material changes necessary being those to the water jacket.

Having thus described my invention in an embodiment thereof and the method of operation therefor, I am aware that numerous and extensive departures may be made therefrom but without departing from the spirit of my invention.

I claim:

1. A furnace, including a cylindrical casing, a pair of spaced parallel walls separating said casing to provide opposite chambers and an air space therebetween, a fire box disposed in each chamber including superposed portions supported thereby in spaced relation to said casing, grates disposed in the bottom of the fire box and an ash pit therebelow, a flue opening disposed in the rear at the upper end of each chamber and ash pit, a stack conduit connecting the upper openings to said stack, downwardly extending tortuous conduits connecting each of the first mentioned conduits to the ash pit opening of the adjacent chamber, and dampers in each of said first mentioned conduits adapted to 130

maintain the passage to the stack closed and the passage to the ash pit of the opposite chamber open or vice versa.

2. A furnace, including a cylindrical casing, a pair of spaced parallel walls separating said casing to provide opposite chambers and having an air space therebetween, a fire box disposed in each chamber including superposed portions supported thereby in spaced relation to said casing, grates disposed in the bottom of the fire box and an ash pit therebelow, a flue opening disposed in the rear at the upper end of each chamber and ash pit, a stack, conduits connecting the upper openings to said stack downwardly extending conduits connecting each of the first mentioned conduits to the ash pit opening of the adjacent chamber, and dampers in each of said first mentioned conduits, separate rotatable shafts supporting said dampers and gear segments keyed to each shaft and in mesh with each other, said dampers and gear segments co-operating to maintain one of said chambers open directly to the stack and the other open to the ash pit of the opposite chamber and a hand lever for operating the same.

3. A furnace, including a cylindrical casing, a pair of spaced parallel walls separating said casing to provide opposite chambers and an air space therebetween, a fire box disposed in each chamber including superposed portions supported thereby in spaced relation to said casing, grates disposed in the bottom of the fire box and an ash pit therebelow, means whereby said fire box portions may be removed and replaced through the ash pit, flue openings disposed in the rear at the upper end of each chamber and ash pit, conduits connecting the upper openings to a common stack, downwardly extending conduits connecting each of the first mentioned conduits to the ash pit opening of the adjacent chamber, co-operating valves in each of said first mentioned conduits adapted to maintain the passage to the stack closed and the passage to the ash pit of the opposite chamber open or vice versa, and to maintain one of said chambers open directly to the stack and the other closed to the ash pit of the opposite chamber, and a non-rigid expanding seal between the fire pot and the casing constraining the gases to go through the fire pot.

4. A furnace, including a casing, a pair of spaced parallel walls dividing said casing into separate chambers having a space therebetween, a fire box in each chamber comprising a pair of superposed fire pot portions, means to removably support said fire pot comprising cleats upon which the lower fire pot portion may rest, and a non-rigid expanding seal between the fire pot and the casing, constraining the gases to go through the fire pot.

5. A furnace including a casing, a pair of

spaced parallel walls dividing said casing into separate chambers having a space therebetween, a fire box in each chamber comprising a pair of superposed fire pot portions, means to removably support said fire pot comprising cleats upon which the lower fire pot portion may rest, and a non-rigid expanding seal between the fire pot and the casing, constraining the gases to go through the fire pot and maintaining the upper fire pot in spaced relation from the casing wall.

6. A furnace, including a cylindrical casing, a pair of spaced parallel walls separating said casing to provide opposite chambers and an air space therebetween, said air space being closed and spaced from the bottom air inlets adjacent said closure and an outlet at the top, a fire box disposed in each chamber including superposed portions supported thereby in spaced relation to said casing, grates disposed in the bottom of the fire box and an ash pit therebelow, a flue opening disposed in the rear at the upper end of each chamber and ash pit, a stack conduit connecting the upper openings to said stack, downwardly extending tortuous conduits connecting each of the first mentioned conduits to the ash pit opening of the adjacent chamber, and dampers in each of said first mentioned conduits adapted to maintain the passage to the stack closed and the passage to the ash pit of the opposite chamber open or vice versa.

In testimony whereof I hereunto affix my signature this 25th day of September, 1929.

EMIL F. SCHONBERGER.
